UNITED STATES PATENT OFFICE.

JOSEPH A. FILER, OF NEW YORK, N. Y.

DESIGN FOR A LACE-HEADING.

SPECIFICATION forming part of Design No. 27,710, dated September 28, 1897.

Application filed June 28, 1897. Serial No. 642,752. Term of patent 3½ years.

To all whom it may concern:

Be it known that I, JOSEPH A. FILER, of New York city, in the county and State of New York, have invented and produced a new and original Design for a Lace-Heading, of which the following is a full, clear, and exact specification.

The invention relates to trimmings, and is to be used as a fancy corner decoration for table-covers, sofa-pillows, and like articles.

Reference is to be had to the accompanying drawing, forming a part of this specification, in which the figure is a face view of a trimming embodying my design.

The leading feature of the design consists of the ornamental band A and the triangular open network B, extending from the said band with the base at the band, as is plainly shown in the drawing. From the apex of the network extends a pendant C in the form of a tassel or the like.

I claim—

The design for a lace-heading, as herein shown and described.

JOSEPH A. FILER.
